UNITED STATES PATENT OFFICE.

EDWIN CHAMBERLIN AND ANDREW M. GARDNER, OF AVELLA, PENNSYLVANIA; SAID CHAMBERLIN ASSIGNOR TO SAID GARDNER.

LIQUID-ELEVATING APPARATUS.

1,131,209.

Specification of Letters Patent.

Patented Mar. 9, 1915.

Application filed May 27, 1913. Serial No. 770,151.

To all whom it may concern:

Be it known that we, EDWIN CHAMBERLIN and ANDREW M. GARDNER, citizens of the United States, residing at Avella, in the 5 county of Washington and State of Pennsylvania, have invented certain new and useful Improvements in Liquid-Elevating Apparatus, of which the following is a specification.

10 The prime object of our invention is to provide a simple, efficient, and automatically operable elevating apparatus.

In the accompanying drawings, which illustrate an application of my invention,

15 Figure 1 is a central vertical sectional view of an apparatus constructed in accordance with our invention; Fig. 2 is a detail central vertical sectional view of the air intake valve mechanism and a portion of the 20 actuating means therefor; Fig. 3 is a horizontal sectional view taken on line III—III of Fig. 2 looking in the direction of the arrows; Fig. 4 is a detailed elevational view of a portion of the inlet valve actuating 25 mechanism and adjusting means for controlling the movement of the valve actuating mechanism; Fig. 5 is a central vertical sectional view of the air exhaust valve mechanism employed; and Fig. 6 is a part sectional view of the air exhaust valve mechanism, the section being taken on line VI—VI of Fig. 5.

30 Referring to the drawings, 1 designates a tank adapted to be submerged or partly submerged in the water to be elevated, and, as illustrated and as preferred, is provided with water inlet valves 2 and 3.

4 designates a water discharge pipe leading from the bottom of the tank and 5 a 40 spring controlled valve controlling the flow of water through pipe 4.

45 Our apparatus is particularly designed for raising or removing water from mines, although it may, of course, be used for raising water or other liquids wherever desired.

The apparatus is designed for use in connection with compressed air, and 6 designates a pipe leading from an air compressor, located at any suitable point, to an air inlet 50 valve mechanism comprising, as illustrated and as preferred, a casing 7 having an interior seat 8 adapted to receive a ball valve 9. Casing 7 is formed with a central bore or

opening 10 designed to receive a stem 11. This valve stem 11 passes through a plug 55 cap 12, the latter closing the lower end of the casing.

13 designates a guide for the stem 11, and located between the lower end of the said guide 13 and the upper end of the plug 60 12, we provide a compression spring 14, the function of spring 14 being to maintain the stem 11 up into engagement with the ball 9 after it has been moved upwardly by the air inlet valve actuating mechanism, herein- 65 after described. Located on the opposite side of the tank from the inlet valve mechanism, we provide an air exhaust mechanism, said latter mechanism being connected by a pipe 15 to the inlet valve to enable the com- 70 pressed air to be passed from the inlet to the exhaust valve mechanism.

The exhaust valve mechanism, as illustrated, comprises a casing 16 having a horizontally disposed outlet chamber 17 and a 75 nozzle 18, the latter being adapted to be extended through a side of the tank and be connected with an exhaust air outlet pipe 19. The lower end of the casing 16 is closed by a cap 20, the latter having a contracted nozzle 80 21 adapted to be connected with a coupling member 22, said coupling member 22 in turn being connected with the pipe 15. Coupling member 22 is provided with a reducing nozzle 23 through which the compressed air is 85 discharged into the interior of the tank.

Located within the interior of the casing 16, we provide a spring controlled plunger 24, said plunger 24 being provided with a stem 25 adapted, as the plunger 24 is raised, 90 to pass through a guide 26, and, interposed between said guide 26 and the plunger, we provide a spring 27. The casing 16 is provided with a series of ports 28 designed, when the plunger or piston 24 is in its low- 95 ered position, to permit the passage of air from the interior of the tank to the air outlet nozzle 18. When the plunger is raised by the compressed air, said air ports 28 are closed, thereby cutting off the escape of air 100 from the interior of the tank.

The air inlet valve mechanism is actuated by means of a float controlled mechanism comprising a float 29, a pivoted rod 30 having its inner end pivotally secured to a block 105 31, said block 31 being provided with a

threaded stem 32 adapted to project through a wall of the tank and be secured thereto by means of a nut 33. The rod 30 is connected with the valve stem 11 by adjustable mechanism comprising member 34, the latter having bifurcated end portions 35 and 36, the ends 35 being formed with openings to receive a pin 37 passed through the rod 30 and the said arms 35. Interposed between 10 the upper spaced ends 36 of member 34 and the stem 11, we provide a block or link 38. This block or link 38 is connected with the arms 36 by a pin 39, the latter being adapted to rest upon an adjusting screw 40 disposed 15 in the lower end of the block 38, and adapted to coöperate with a threaded opening 41 of the block and into which the screw 40 is entered. The upper end of the block or link 38 is provided with a threaded opening 20 adapted to receive the threaded lower end 42 of the valve stem 11.

43 designates an adjusting nut arranged to coöperate with the threaded portion 42 of valve stem 11 and bear upon the upper face 25 of the block 38. By means of the adjusting mechanism connecting the valve stem 11 and the rod 30, we are enabled to cut off the supply of air at any desired position of the float, and thus regulate to a nicety the 30 quantity of compressed air necessary to effectively operate the apparatus.

Assuming that the water or other liquid has entered the tank to a predetermined level, the air inlet valve 9 is raised from its 35 seat by the valve actuating mechanism, thus permitting compressed air to be passed from the air inlet valve casing 7 to the pipe 15 and from pipe 15 to the exhaust valve mechanism. The compressed air raises the plunger 24, thereby closing the ports 28 and preventing the escape of air from the interior of the tank. Simultaneously with the moving of plunger 24, the compressed air discharges through the contracted nozzle 23 40 expanding and forcing the liquid contents of the tank out through the discharge pipe. The descent of the ball float draws the valve operating stem 11 downwardly out of contact with the ball valve 9, thereby permitting said valve 9 to drop upon its seat and cut off the supply of air to the tank.

After the air has been cut off, as above described, the expansion of the air within the tank will force all the liquid in the tank 55 out through the discharge pipe. After the liquid has been discharged, the pressure within the tank is reduced sufficiently to enable the spring 27 to move the plunger 24 downwardly past the ports 28, thereby enabling the contained air to pass from the interior of the tank outwardly to the atmosphere through the outlet nozzle 18. By this arrangement, it will be noted that we are 60 enabled to save a considerable quantity of air, for it will be noted that the air intro-

duced prior to cutting off the supply of air will expand and operate as above described.

What we claim is:

1. In a liquid elevating apparatus, the combination with a tank, of automatically 70 operable air inlet and exhaust valve mechanisms, a pipe for air leading from the inlet to the exhaust valve mechanism, said exhaust valve mechanism including a plunger adapted to be operated by the air from the 75 inlet valve mechanism, means for actuating the inlet valve mechanism including a float and adjustable means intermediate the float and the inlet valve mechanism, a liquid intake valve within the tank, and a liquid discharge pipe. 80

2. In a liquid elevating apparatus, a submersible tank having air inlet and exhaust pipes, automatically operable air inlet valve mechanism, means for actuating the inlet 85 valve mechanism, an air exhaust valve mechanism, a pipe in the tank leading from the air inlet to the air exhaust valve mechanism, said exhaust valve being in communication with said pipe and actuated by air therefrom means coöoperating with the pipe for directing air to the exhaust valve mechanism and to the interior of the tank, a liquid intake valve for the tank, and a liquid discharge pipe, said tank constituting a 90 housing for the above mentioned elements. 95

3. In a liquid elevating apparatus, a submersible tank having air inlet and exhaust pipes, automatically operable air inlet valve mechanism, means for actuating the inlet 100 valve mechanism, an air exhaust valve mechanism, a pipe for air leading from the air inlet to the air exhaust valve mechanism, means coöoperating with the pipe for directing air to the exhaust valve mechanism and to the interior of the tank, a liquid intake valve for the tank, and a liquid discharge pipe, said tank constituting a housing for 105 the above-mentioned elements.

4. In a liquid elevating apparatus, the 110 combination with a tank, of automatically operable air inlet and exhaust valve mechanism, means for actuating the inlet valve mechanism including a float and intermediate adjustable means, a pipe for air leading 115 from the inlet to the exhaust valve mechanism, means coöoperating with the pipe for directing air to the exhaust valve mechanism and the interior of the tank, a liquid intake valve within the tank, and a liquid 120 discharge pipe.

5. In a liquid elevating apparatus, the combination with a submersible tank, of automatically operable air inlet and air exhaust valve mechanisms, means for actuating the inlet valve mechanism including a float, a pipe for conveying air from the inlet valve to the exhaust valve, means coöperating with the pipe for directing air to the exhaust valve and to the interior of the 125 130

tank, inwardly opening valves in the wall of the tank to admit liquid to the tank, and a liquid discharge.

6. In a liquid elevating apparatus, the combination with a submersible tank, of automatically operable air inlet and air exhaust valve mechanism, means for actuating the inlet valve mechanism including a float, a pipe for conveying air from the inlet valve to the exhaust valve, means coöperating with the pipe for directing air to the ex-

haust valve and to the interior of the tank, valves to admit liquid to the tank, and a liquid discharge.

In testimony whereof we affix our signatures in presence of two witnesses.

EDWIN CHAMBERLIN. [L. S.]
ANDREW M. GARDNER. [L. S.]
